UNITED STATES PATENT OFFICE.

HENRY V. SCANDRETT, OF SPEARVILLE, KANSAS, ASSIGNOR OF ONE-HALF
TO GEORGE H. STEELE, OF SAME PLACE.

DESIGN FOR A BICYCLE HANDLE-BAR.

SPECIFICATION forming part of Design No. 30,821, dated May 16, 1899.

Application filed October 5, 1898. Serial No. 692,758. Term of patent 7 years.

To all whom it may concern:

Be it known that I, HENRY V. SCANDRETT, a citizen of the United States, residing at Spearville, in the county of Ford and State of Kansas, have invented and produced a new and original Design for Bicycle Handle-Bars, of which the following is a specification, reference being had to the accompanying drawings, which fully illustrate a handle-bar constructed in accordance with my design.

Figure 1 is a front elevation of my design, and Fig. 2 is a top plan view of the central portion thereof.

Referring to the drawings, A represents a vertical cylindrical depending portion of the handle-bar, encircling which is the circumferential body A', having at its front side a

similar body C. Extending from either face of this body C are the handle-bars B, each handle-bar being curved upwardly, as shown at B', then outwardly, as shown at B'', and tapering all the while, the taper becoming more pronounced as it approaches the end, as shown at B''', and at the end of each bar is designed a cylindrical tip or grip D.

Having thus fully described my invention, what I claim as new, and desire to secure by Letters Patent, is—

The design of a bicycle handle-bar, substantially as herein shown and described.

HENRY V. SCANDRETT.
